UNITED STATES PATENT OFFICE.

ELMER J. BEEBE AND CLIDE C. MACGREGOR, OF FLINT, MICHIGAN.

COMBINATION FREIGHT AND GRAIN CAR.

1,239,863.

Specification of Letters Patent. Patented Sept. 11, 1917.

Application filed November 15, 1916. Serial No. 131,536.

To all whom it may concern:

Be it known that we, ELMER J. BEEBE and CLIDE C. MACGREGOR, citizens of the United States, residing at Flint, in the county of Genesee, State of Michigan, have invented a new and useful Combination Freight and Grain Car; and we do hereby declare the following to be a full, clear, and exact description of the invention, such as will enable others skilled in the art to which it appertains to make and use the same.

This invention relates to the art of rolling stock, and especially to freight cars, and more particularly to a bottom dump, and opposite side grain car doors, whereby the freight car is convertible into a grain car, and vice versa.

One of the objects of the invention is to provide an improved bottom dump for cars, the opposite ends of the bottom being inclined, and having discharge openings adjacent where the inclined parts of the bottom meet, said openings being controlled by sliding doors.

25 A further object of the invention is to provide hinged members on the interior of the car to be thrown down, to cover the inclined portions of the bottom, and assist in providing a flat bottom.

30 A further object of the invention is to provide opposite grain car doors each consisting of two sections, one slideable in guide grooves of the other section, which is hinged adjacent the bottom of the door opening, so that this other section may be thrown down, that is one thrown down from each side, in order to complete the flat bottom, in which case the car may be used for freight, and in this case the car may be provided with the usual exterior sliding doors, not shown. However, when the hinged section is in vertical position, the slideable section may be adjusted in different vertical positions, as the car becomes filled with grain.

45 A further object of the invention is to provide means for raising and lowering the hinged section on its hinges.

50 A further object is to provide means for raising and lowering the slideable section of the hinged section.

In practical fields, the details of construction may necessitate alterations falling within the scope of what is claimed.

55 The invention comprises further features and combinations of parts, as hereinafter

set forth, shown in the drawings, and claimed.

In the drawings:—

Figure 1 is a view in side elevation of a car having a bottom dump and sectional side drawers, and hinged bottom members, which coöperate with one of the sections of each side door, whereby the car may be converted into a grain car or a freight car.

Fig. 2 is a sectional view on line 2—2 of Fig. 1, showing the parts in plan.

Fig. 3 is a longitudinal section view on 3—3 of Fig. 2.

Fig. 4 is a bottom plan view of the car.

Referring more especially to the drawings, 1 designates a car, which may be constructed of any suitable material, preferably sheet metal, and of any suitable configuration. The bottom of the car adjacent both ends is horizontal for a short distance, and extending from these horizontal portions, 2 are the bottom parts 3, which are inclined downwardly and toward each other to the center of the car, thereby affording inclined chutes, which, in cross section, are inclined 70 toward and terminate in the discharge openings 4. Surrounding each opening 4 is a tubular member 5 having a flange 6. Each tubular member 5 is provided with a swiveled chute 7, which comprises the inclined part 8, which inclines from the 75 enclosed end 9 of said chute 7 to and toward the open end 10. The top 11 of the chute 7 has an opening 12, which receives the tubular part 5, so that the top 11 may rest 80 upon the flange 6, whereby the chute 7 may be turned to dump the grain either directly under the car or toward either side. Upon the under surfaces of the inclined portions 3, guides 13 are provided, in which the 85 sliding doors 14 are mounted. Each door is provided with a rack 15.

Mounted in bearings 16 adjacent the sides of the car, are shafts 17, which are supplied with gears 18, to engage said racks 15. 100 Upon the ends of each shaft 17 are hand wheels 19, whereby the turning of either one, will rotate its respective shaft, and through the medium of its gear 18, the sliding door will be moved in its guide, in order 105 to open or close its respective discharge opening. It is to be observed that the sliding doors 14 move transversely of said tubular parts 5, to close said discharge openings 4. Mounted in bearings 20 adja- 110

cent the lower side portions of the car are rock shafts 21, there being collars 22 on said rock shafts to prevent axial movement. The opposite ends of each rock shaft 5 are provided with right angle extending arms 23, and fixed to one end of each rock shaft, is a pawl 24, designed to engage the teeth of the ratchet 25, which is upon one end of each shaft 17. It is to be noted that 10 each rock rod or shaft 21 may be rocked partially from either end, by grasping one of the handles or arms 23, to cause the pawl 24 to engage or disengage its ratchet. When the pawl is in engagement with its 15 ratchet, the door 14 may be opened, by reason of the pawl ratcheting over the teeth. However, the pawl will prevent the door 14 from closing. By disengaging the pawl, the door may be opened or closed freely. 20 The bottom of the interior of the car is provided with a centrally located partition 26, which consists of the two walls 27, and is adjacent where the inclined portions 3 substantially join. The bottom portions 2 25 and the inclined bottom portions 3 are reinforced or strengthened by means of the longitudinally extending eye beams 28, the central parts of which are engaged and fixed in any suitable manner to the central 30 partition 26, as shown in the drawings.

The sides of the car are provided with the usual door openings 29, and the inner face of each side near the upper portions of the edges of each door opening are overhanging flanges 30 forming guides 31. The edge of one of the flanges of each door opening 29 have ratchet teeth 31^a. Mounted upon hinges 32 near the bottom of each door opening 29 is a grain car door section 33, 35 and the opposite edges of this section have guides 34, in which a second grain car door section 35 is mounted, and which section 35 may be raised and lowered in the guides 31. Projecting inwardly from the flanges forming 40 the guides 34 are bearings 36, in which the shaft 37 is mounted, and one end of this shaft 37 has a beveled gear 38, while the central portion of this shaft has a gear 39, which is in mesh with the rack 40 on the 45 inner face of the grain car door section 35. Mounted in a bearing of each side of the car near one side or edge of each door opening 29 is a stub shaft 41, the inner end of which is provided with a beveled gear 42, 50 while the outer end is provided with a hand wheel 43. The beveled gear 42 meshes with the beveled gear 38 so that by turning the hand wheel 43, the grain car door section 35 may be raised and lowered in its guides 55 31, there being a gravity or weight actuated pawl 44 pivoted at 45 on the inner face of the car door section 35, so as to ratchet over the teeth 31^a, and to cooperate with any one of said teeth to hold the section 35 in 60 different raised positions. Mounted in 65

bearings 45^a of the under part of the car, at diagonal opposite sides are shafts 46, each having a hand wheel 47. A cable 48 has one end portion secured to and partially wound about each shaft 46 and passes about 70 pulleys 49 and 50, and has its other end connected at 51 to one of the edge portions of the upper part of the door section 33. It is to be noted that by rotating the rod or shaft 46, the door section 33 may be raised 75 and lowered on its hinges 32, that is, when the door section 35 is lowered sufficiently so that it is free of its guides 31, or may be lowered on its hinges, when the section 35 is completely raised in its guides 31. Latches 80 53 are pivoted adjacent the lower parts of the flanges 30, and are designed to overlie the edge portions of the section 33, to hold the section 33 in a raised position, to close the lower part of the door opening 29. It 85 is to be noted that when the door sections 33 are lowered, they assist in forming a part of a flat bottom for the car. Hinged at 54 to the opposite sides of the car and adjacent both door openings 29 are flat bottom sections 55, which may be lowered as shown in Fig. 2, to assist in forming a part of the flat bottom of the car. However, latches 56 are pivoted on the inner faces of the sides of the car to hold these bottom 90 sections 55 raised upon their hinges. Hinged at 57 where the bottom portions 2 terminate are flat bottom sections 58, which may be disposed as shown in Fig. 2, to complete the flat bottom of the car. When the 100 car is used as a hopper car the doors or bottom sections 58 are swung upwardly and toward the ends of the car and down against the inclined ledges 2^a of the opposite sides of the car, which ledges are shown in 105 Figs. 2 and 3 of the drawing. The inner end of the cable 48 is provided with a ring, which may be connected to or disconnected from either of the hooks 51 and 59. When the ring of the cable 48 is connected to the 110 hook 51, the door section 33 may be raised and lowered on its hinges, but when the ring of said cable is connected to the hook 59, the door section 33 is used to form a part of the flat bottom of the car. The bottom hinged sections 58 are provided with knobs 60, to be manually grasped for raising said sections. 115

The invention having been set forth, what is claimed as new and useful is:— 120

1. In a bottom dump mechanism for cars, the combination of a hopper bottom having flanged discharge openings and chutes swiveled to the flanges of said discharge openings, of means for closing said discharge 125 openings.

2. In a bottom dump mechanism for cars, the combination of a hopper bottom having flanged discharge openings and chutes swiveled to the flanges of said discharge open- 130

ings, of means for closing said discharge openings, said means comprising guides upon said hopper bottom extending from said openings toward the ends of the car, 5 slides or closures in said guides, and means for operating said slides or closures.

3. In a bottom dump mechanism for cars, the combination of a hopper bottom having flanged discharge openings and chutes swiveled to the flanges of said discharge openings, of means for closing said discharge openings, said means comprising guides upon said hopper bottom extending from said openings toward the ends of the car, 10 slides or closures in said guides, and means for operating said slides or closures, said operating means comprising racks on said slides or closures, shafts mounted in bearings of the hopper bottom and having pins 15 to engage said racks, and provided with hand wheels for rotating the shafts, one end of each shaft having a ratchet, rocking rods mounted in bearings of the hopper bottom and provided with pawls to engage said 20 ratchets to hold the closures in open positions.

4. In a bottom dump mechanism for cars, the combination of a hopper bottom having flanged discharge openings and chutes swiveled to the flanges of said discharge openings, of a division wall separating said discharge openings, and means comprising flat bottom sections foldable from the ends and the sides of the car over the hopper bottom, 25 to form a flat bottom, thereby converting the bottom dump car into a freight car.

5. In a grain car door, a car door opening, a grain car door consisting of two sections, one section being hinged at the bottom of said opening and having guides at its 30 opposite ends in which the other section is adjustably mounted, and means whereby the hinged section may be tilted upwardly and downwardly on its hinges, when said other section is lowered completely in its guides.

6. In a grain car door, a car door opening, a grain car door consisting of two sections, one section being hinged at the bottom of said opening and having guides at its 35 opposite ends in which the other section is adjustably mounted, the upper portions of 50

the side edges of the door opening having guides to receive the section that is mounted in the guides of the hinged section, when the hinged section is closed.

55

7. In a grain car door, a car door opening, a grain car door consisting of two sections, one section being hinged at the bottom of said opening and having guides at its 60 opposite ends in which the other section is adjustably mounted, the upper portions of the side edges of the door opening having guides to receive the section that is mounted in the guides of the hinged section, when the hinged section is closed, said 65 slideable section having a rack, a shaft mounted in bearings of the hinged section and provided with a gear to engage said rack, a beveled gear on one end of said shaft, and means to engage said beveled gear to rotate the 70 shaft to raise the slideable section.

8. In a grain car door, a car door opening, a grain car door consisting of two sections, one section being hinged at the bottom of said opening and having guides at its 75 opposite ends in which the other section is adjustably mounted, the upper portions of the side edges of the door opening having guides to receive the section that is mounted in the guides of the hinged section, when 80 the hinged section is closed, said slideable section having a rack, a shaft mounted in bearings of the hinged section, and provided with a gear to engage said rack, a beveled gear on one end of said shaft, and means 85 to engage said beveled gear to rotate the shaft to raise the slideable section, one of the guides of the upper parts of one side edge of the door opening having ratchet teeth, and means carried by the slideable section 90 consisting of a pawl to engage the teeth of the ratchet bar on the slideable section, to hold the slideable section in different adjusted positions when raised.

In testimony whereof we have signed our 95 names to this specification in the presence of two subscribing witnesses.
